FRINGE FOR A MUSICAL INSTRUMENT

Rudolph Dopera, 18906 Normandie Ave.,
Gardena, Calif. 90247

Filed Dec. 15, 1971, Ser. No. 208,538

Term of patent 14 years

Int. Cl. D5—08

U.S. Cl. D3—32 E

FIG. 1 is a front elevational view of a fringe for a musical instrument showing my new design; and

FIG. 2 is a front perspective view thereof on a reduced scale, the broken line showing of a musical instrument being for purposes of illustration only.

I claim:

The ornamental design for a fringe for a musical instrument, as shown and described.
